UNITED STATES PATENT OFFICE.

LEIF LEE, OF YOUNGSTOWN, OHIO, ASSIGNOR TO GEORGE MESTA, OF PITTSBURGH, PENNSYLVANIA.

OPERATING MECHANISM FOR WEIGHT-SUPPORTING PLUNGERS.

Application filed September 2, 1922. Serial No. 585,974.

To all whom it may concern:

Be it known that I, LEIF LEE, a citizen of the United States, and a resident of Youngstown, in the county of Mahoning and the State of Ohio, have made a new and useful Invention in Operating Mechanism for Weight-Supporting Plungers, of which the following is a specification.

This invention relates to operating mechanisms for machines, such as pickling machines, and has for an object to produce a mechanism of simple construction which is more effective and efficient in operation than similar mechanisms now in use and known to me.

Pickling machines are ordinarily so arranged that they are capable of being operated to move metal articles into and out of the pickling vats and to agitate the articles while in the pickling solution. Such an arrangement of apparatus is advantageous, since it eliminates the necessity of re-handling the articles subjected to the pickling solution, and also renders the pickling operation more uniform.

A further object of my invention is therefore to provide a simple and effective operating mechanism which may be employed in connection with a pickling machine in lowering metal articles into the pickling solution, agitating the articles while in the solution and lifting the articles from the solution.

A further and more specific object of the invention is to produce an operating mechanism for metal pickling machines which is simpler and less costly to manufacture and operate than apparatus now in use and known to me.

In the drawings accompanying and forming a part hereof, Figure 1 diagrammatically illustrates a pickling machine equipped with my invention; several details of the machine and operating mechanism embodying my invention are shown in section for convenience of illustration.

Figure 2 is a fragmental view of apparatus embodying a modification of my invention.

Referring to the drawings, the pickling machine includes a weight-supporting plunger 3 which is mounted in a vertical support or guide 4 and is equipped with two or more horizontally extending arms 5. The arms 5 are adapted to support trays or

frames 6 for receiving the metal articles to be pickled. These frames are preferably formed of acid proof metal and as shown, are suspended from the arms 5 by means of chains or cables 7.

In the illustrated embodiment, the plunger 3 extends vertically through its support or guide 4 and its lower end projects into a chamber 8 formed within the support 4. A port 9 is provided in the lower end of the chamber through which actuating fluid or liquid is delivered to the chamber. I preferably employ a non-compressible fluid such as water as the actuating fluid for the plunger. In the apparatus illustrated in Figure 1 the actuating liquid is delivered to the pressure chamber 8 by means of a constantly operating pump 10 which, as illustrated, comprises piston 11 and its associated cylinder 12.

I have shown a valve mechanism capable of automatic and manual control for controlling the operation of the pump 10, so that it functions either as a pump in delivering actuating fluid to the chamber 8, or as a pulsator for the purpose of imparting pulsations to the chamber 8. The valve mechanism is also capable of rendering the pump 10 inoperative so that it neither transfers liquid nor pulsations to the chamber 8.

As illustrated, the valve mechanism includes a valve casing 13 in which two valves 14 and 15 are mounted. The casing is provided with a port 16 which communicates with the interior of the cylinder 12 through a pipe or passage 17. A port 18 formed in the casing communicates with the port 9 of the pressure chamber 8 through a pipe or passage 19. Communication between these two ports is controlled by the valve 14. The casing is also provided with a port 20 which communicates, through a pipe or passage 21, with a receptacle or sump 22 which forms a source of supply for the actuating liquid. A passage 23 formed within the casing is so located and arranged that it is adapted to establish communication between the ports 20, 16 and 18, when the valves 14 and 15 are raised from their seats.

In the illustrated embodiment, a cam bar 24 is employed for controlling the operation of the valves 14 and 15. As shown, this bar is mounted on the casing 13 by means of brackets or rollers 25 and is adapted to be moved to different positions with relation to

the casing. The bar is provided with three cam lobes 26, 27 and 28, so arranged that one or both of the valves 14 and 15 may be rendered inoperative.

- 5 As shown, the valve 15 is provided with a valve stem 29 which projects through the casing. A roller 30 is so mounted on the stem 29 that it will lift the valve 14 off of its seat and hold it in an inoperative position when engaged by either of the cam lobes 26 or 27 of the bar 24. The roller is however so located on the stem 29 and so correlated with the bar 24 that it will not interfere with the pressure responsive operation 15 of the valve 14 unless engaged by one or the other of the above-mentioned cam lobes.

The valve 15 is provided with a roller 31 which is similarly arranged with relation to its valve stem 32. The roller 31 is adapted to be engaged by the cam lobe 28 for the purpose of lifting the valve 15 off of its seat, but is so arranged that it does not interfere with the pressure responsive operation of the valve 15 when not engaged by the 25 cam lobe.

As illustrated, the cam bar is adapted to be actuated by means of a bell crank 34 through the agency of a rod 35. The bell crank is pivotally mounted on a bracket carried by the support 4 and is provided with a bifurcated arm 36, which straddles a rod 37 carried by the plunger 3. The rod is provided with two stops 38 and 39 which are adapted to engage and actuate the lever 34 35 for the purpose of automatically limiting the travel of the plunger 3.

As shown, the apparatus is so arranged that the trays or frames 6 are located in pickling vats 40 when the support plunger 40 is in its lowermost position. When it is desired to raise the frames out of the vats the cam bar 24 is shifted to the position illustrated in Fig. 1. Under such conditions the pump 10 operates as a pump drawing liquid from the sump 22 and forcing it into the pressure chamber 8. It will be apparent that during the suction stroke of the pump, the valve 15 opens in response to the reduction in pressure within the pump cylinder 45 thereby drawing liquid from the sump into the cylinder 12 or the communicating passages. During the pressure stroke of the piston 11 the valve 15 seats and the valve 14 lifts, thereby causing liquid to be forced 50 into the pressure chamber 8. This causes the plunger 3 to rise and lifts the frames out of the pickling vats. In lowering the frames into the vats both valves 14 and 15 are lifted from their seats. This is accomplished by 55 shifting the cam bar so that the lobe 27 engages the roller 30 and the lobe 28 engages the roller 31. Under such conditions the chamber 8 is placed in open communication 60 with the sump 22 and the pressure of the plunger forces the actuating liquid from the 65

chamber 8 to the sump. As the plunger moves downwardly the stop 38 carried by the rod 37 moves downwardly with it and finally engages the arm 36 of bell crank 34 thereby shifting the cam bar to the position 70 illustrated in Fig. 1. This cuts off communication between the chamber 8 and the sump 22 since it permits both valves 14 and 15 to move to their seats.

When it is desired to impart pulsations to 75 the chamber 8 for the purpose of oscillating the trays 6 and thereby agitating the articles located in the pickling solution, the cam bar is shifted to a position in which the lobe 26 engages the roller 30 and thereby 80 lifts the valve 14 from its seat. This is accomplished by manually shifting the position of the bell crank 34. Under such conditions the operating piston 11 occasions 85 variations or pulsations in the liquid within the chamber 8 and which cause the support piston 3 to move up and down in substantial synchronism with the piston 11, the amount of movement being in direct proportion to the displacement of the piston 11 and 90 plunger 3.

The stop 39 limits the upward movement 95 of the plunger 3 while the pump 10 is functioning as a pump, since it moves into contact with the arm 36 of the bell crank 34, thereby shifting the position of the cam bar 24 from that shown in the drawings to a position in which both valves 14 and 15 are lifted from their seats by the cam lobes 27 and 28. After the travel of the plunger 3 100 has been stopped by the automatic action of one of the stops 38 or 39, the movement of the plunger 3 is reversed by a manual shifting of the bell crank and a consequent readjustment of the valves 14 and 15. 105

It will be apparent that any means may be employed for driving the pump 10. As illustrated, the piston 11 is provided with a piston rod 42 which is driven by a motor 44 in the usual manner. The usual means may 110 be employed for starting and stopping the motor.

In Fig. 2 I have illustrated apparatus which may be employed with a portion of the apparatus shown in Fig. 1 for the purpose of accomplishing the results above described. As shown, an accumulator 45 is adapted to be employed as the source of pressure for lifting the support plunger 3. This renders the valves 14 and 15 and their operating mechanism unnecessary and they may be dispensed with where an accumulator is employed. As shown in Figure 2, the pipe or passage 19, communicating with the pressure chamber 8 may communicate directly with the pipe or passage 17, communicating with cylinder 12 and the accumulator may be so arranged as to be placed in communication with both of these pipes. As illustrated, a pipe or passage 46 130

is adapted to establish communication between the accumulator 45 and chamber 8. A three-way valve 47 is preferably so located within this pipe that when turned 5 to one position the accumulator communicates directly with the pipes 17 and 19, when turned to the other position the pipe 19 and consequently the pressure chamber 8 is placed in open communication with an 10 exhaust pipe or passage 48 which may communicate with a sump. It will be apparent that the trays or frames 6 may therefore be raised or lowered by the manipulation 15 of the three-way valve, since the accumulator will force liquid into the chamber 8 when the valve 47 is turned to place it in communication with the pipe 19, and the weight of the plunger 3 will force the liquid from the chamber 8 when the valve 20 47 is turned to the position illustrated in Figure 2. The three-way valve may also be turned to a third position in which the pipe 19 neither communicates with the accumulator nor with the exhaust pipe and 25 when in this position the piston 11 may be employed as heretofore described for the purpose of imparting pulsations to the interior of the pressure chamber 3. As shown, the motor 44 is provided with a fly 30 wheel 43 for storing up energy during the operation of the piston 11. It will be apparent that while the pump 10 is operating as a pulsator the piston 11 is at all times subjected to the pressure occasioned 35 by the weight of the plunger 3 and the apparatus carried by it, consequently the fly wheel 43 stores up energy imparted to the piston during its backward strokes, and in this way minimizes the power necessary for 40 pulsating the plunger 3.

It will of course be understood that various changes, modifications and omissions may be made in the apparatus illustrated without departing from the spirit and scope of the invention as defined by the appended claims.

What I claim is:

1. In combination with a weight supporting plunger of a machine, a pressure chamber into which said plunger projects, means for delivering actuating fluid to the chamber to support the plunger in different position with relation thereto, and means for delivering pulsations to said fluid with- 50 in the chamber to reciprocate the plunger.

2. In combination with a weight supporting plunger, a pressure chamber into which said plunger projects, means for delivering fluid under pressure to said chamber, and 55 means for occasioning periodic pulsations in the fluid within the chamber to occasion periodic reciprocations of the plunger.

3. In combination with a weight supporting plunger, a pressure chamber into which 60 said plunger projects, means for subjecting

said chamber to fluid pressure and means comprising a reciprocating piston for occasioning pulsations in the fluid within said chamber.

4. In combination with a weight supporting plunger, a pressure chamber into which said plunger projects, means for subjecting said chamber to hydraulic pressure for the purpose of hydraulically supporting the plunger, and a pump associated with a 70 closed circuit including said chamber for imparting pulsations to the plunger.

5. In combination with a weight supporting plunger of a machine, a pressure chamber into which said plunger projects, means 80 for delivering fluid under pressure to the chamber and a constantly moving element for occasioning pulsations in the fluid within said chamber.

6. In combination with a weight supporting plunger of a machine, a pressure chamber, means for delivering pulsations to the fluid under pressure in said chamber, and means for controlling the delivery of fluid from said first mentioned means to said 85 chamber whereby successive pulsations are caused to successively increase the volume of the fluid within said chamber.

7. In combination with a weight supporting plunger of a machine, a pressure chamber into which said plunger extends, means comprising a reciprocating plunger and an enclosing cylinder for delivering liquid under pressure to said chamber, and a valve mechanism between said chamber and said 95 cylinder for controlling the operation of said means whereby the volume of the fluid within said chamber is successively increased by the reciprocations of said plunger or is alternately increased or decreased 100 in synchronism with the reciprocations of said plunger.

8. In combination with the tray supporting plunger of a pickling machine, a chamber into which said plunger projects, means 110 for delivering fluid under pressure to said chamber to support and actuate said plunger, and means for controlling the operation of said first mentioned means whereby periodic pulsations are imparted to the fluid 115 within said chamber.

9. In combination with the tray supporting plunger of a pickling machine, a chamber into which said plunger projects, means for confining fluid under pressure within 120 said chamber to support said plunger, and a reciprocating piston for imparting pulsations to the fluid within the chamber to reciprocate the piston.

10. In combination in a pickling machine, 125 a tray supporting plunger, trays supported by said plunger, pickling vats into which said trays are movable, a guide for said plunger provided with a pressure chamber into which said plunger projects, a pump 130

- for delivering actuating fluid to said chamber, an adjustable valve mechanism for controlling the operation of said pump, and means actuated by said plunger for automatically controlling the operation of said valve mechanism.
11. In combination in a pickling machine, a tray supporting plunger, trays supported by said plunger and movable into and out of pickling vats, a guide for said plunger, a pressure chamber into which said plunger projects, a pump for delivering actuating fluid to said chamber to move said plunger, a valve mechanism for controlling the operation of the pump whereby said pump operates to successively increase the volume of liquid delivered to said chamber or to alternately increase and decrease the volume of liquid within said chamber in substantial synchronism with the reciprocations of the pump.
12. In combination in a pickling machine, a tray supporting plunger, a guide for said plunger, a pressure chamber into which said plunger projects, a reciprocating piston and an associated cylinder for delivering actuating fluid to said chamber, a valve mechanism for controlling the operation of said
- piston and cylinder and means for controlling the operation of said valve mechanism whereby actuating fluid discharges from said chamber independently of the operation of said piston and cylinder.
13. In combination in a pickling machine, a tray supporting plunger, a guide for said plunger, a pressure chamber into which said plunger projects, means for maintaining fluid under pressure within said chamber and means for alternately increasing and decreasing the volume of fluid within said chamber to cause said plunger to pulsate.
14. In combination in a pickling machine, a tray supporting plunger, a guide for the plunger, a pressure chamber into which the plunger projects, an accumulator for delivering actuating fluid to said pressure chamber, and a reciprocating piston operatively associated with said pressure chamber for occasioning pulsations of the fluid within said chamber.

In testimony whereof, I have hereunto subscribed my name this 31st day of August, 1922.

LEIF LEE.
